UNITED STATES PATENT OFFICE.

HOMER H. HUNNICUTT, OF GILTNER, NEBRASKA.

DISK-SHARPENING ATTACHMENT.

SPECIFICATION forming part of Letters Patent No. 660,704, dated October 30, 1900.

Application filed March 17, 1900. Serial No. 9,068. (No model.)

To all whom it may concern:

Be it known that I, HOMER H. HUNNICUTT, a citizen of the United States, residing at Giltner, in the county of Hamilton and State of 5 Nebraska, have invented a new and useful Disk-Sharpener Attachment, of which the following is a specification.

This invention relates to disk-sharpener, and the aim of the present improvement is 10 to provide a simple and effective attachment for grinding-machines whereby a disk can be held in close relation to a grinding element and adjustable in horizontal and vertical directions to accommodate various sizes of disks 15 and irregularities in the disk edges, the vertical movement being automatic to maintain the disk edge in close relation to the grinding element.

The invention consists, primarily, in a frame 20 for removable attachment to a grinding or sharpening mechanism having a vertical spindle, on which a disk-support is movably and loosely mounted to swing in a horizontal plane or rise and fall to accommodate the size of 25 the disk or an irregularity in the disk edge, the weight of the support being brought to bear on the disk to hold the latter closely to the grinding element.

The invention further consists in the details 30 of construction and arrangement of the several parts, which will be more fully hereinafter described and claimed.

In the drawings, Figure 1 is a perspective view of a grinding mechanism, showing the 35 improved disk-sharpener attachment applied thereto in operative position. Fig. 2 is a similar view of the improved attachment disconnected and shown on a larger scale.

Similar numerals of reference are employed 40 to indicate corresponding parts in the views.

The numeral 1 designates a stand or upright of the grinding-machine, having arms 2 at the upper extremity thereof provided with suitable bearings or journal-boxes, in which 45 is rotatably mounted a shaft 3, having emery-wheels 4 attached to opposite terminals thereof and adapted to be driven by a belt in engagement with an intermediate belt element 4^a.

50 The improved attachment comprises a frame 5, including a clamping-yoke 6, supplied with a securing bolt or pin 7 and having the re-

maining portion thereof in the form of converged or closely-arranged parallel members 8 to provide an arm 9. The yoke 6 is intended to be removably attached to the stand 1, as shown by Fig. 1, and removably fastened in operative position, so that the arm 9 will occupy a horizontal plane relatively to the said stand, the bolt or pin being slightly curved to correspond to the contour of the surface of the stand with which it engages. The frame 5 also includes a diagonal or oblique-twisted brace 10, which has its lower extremity in engagement with a semicircular clamping-bar 11, provided with opposite screw-threaded terminals 12, adjustably extending through outstanding ears 13 of a correlative clamping-band 14, to which the said clamping-bar is removably fitted on the stand 1 and serves 70 to maintain the entire frame 5 in its adjusted position on the stand. The upper extremity of the brace 10 passes between the members 8 of the arm 9 and terminates in a horizontal table 15, with an aperture therethrough to receive a pivot-bolt 16, extending through a crank-arm 17, which has a vertical spindle 18 rising from its free extremity. The adjustment of the bolt 16 in relation to the table 15 is such that the arm 17 is free to swing or 80 move in a horizontal plane and is held in a truly horizontal position by bearing on the said table.

The vertical spindle 18 provides a fulcrum or pintle for the operation of a disk-support 85 19, which comprises a lower bar 20, having its one extremity apertured, as at 22, and loosely mounted on the said spindle and its outer portion 21 slightly elevated through the medium of an intermediate bend 23 and then 90 continued into a substantially vertical member 34, which terminates in a horizontal handle or grip 25. The greater portion of the bar 20 is flat to accommodate the attachment of other parts thereto, as will be presently 95 explained; but the grip or handle 25 is rounded for convenience in grasping the same. The support 19 also includes an auxiliary member 26, having one terminal extended upwardly in a curved member 27 and apertured, as at 28, 100 to also fit over the spindle 18 to serve as an additional bearing for the support at a point above the engagement with the said spindle of the terminal of the bar 20. From the outer

lower termination of the member 27 an auxiliary member 26 is horizontally arranged, as at 29, and held apart from the adjacent portion of the bar 20 by a vertically-disposed 5 space-sleeve 30 or an analogous device, and through the horizontal portion 29 of the auxiliary the space-sleeve 30 and the adjacent horizontal part of the bar 20 a bolt 31 is vertically passed to separably connect the parts and 10 hold them in spaced relation through the inter-mediation of the sleeve 30. From the outer termination of the horizontal part 29 of the auxiliary 26 the latter is continued up rearward in the form of an arcuate extension 32, having 15 an upper horizontal portion 33, the opposite extremity of said extension being secured to the elevated portion 21 of the bar 20, as at 34. The horizontal portion 33 of the arcuate extension 32 and the part of the bar 20 there- 20 below have a spindle or rod 35, extending vertically therethrough, which is removable and screw-threaded and nutted at its lower extremity, as at 36, and provided with an upper collar 37, which bears against the under 25 side of the horizontal portion 33 of the arcuate extension 32 to afford means for rigidly and positively disposing the said rod in position. The extremity of the rod 35 above the horizontal portion 33 of the arcuate extension 30 is screw-threaded, as at 38, and thereon is 30 movably mounted a bearing-head 39, against which the disk 40 has firm contact and in application is run down over the said screw-threaded extremity 38 and held in place by a 35 nut 41, also applied to said extremity, to thereby hold the disk against vertical movement in order to make the grinding operation effective.

It is intended that the frame 5 be applied 40 to any suitable grinding-machine other than that shown, and it is to be understood that the practical operation of the improved attachment is not dependent upon any form of grinding-machine. The form shown, how- 45 ever, is sufficient to illustrate the practical working of the attachment, and after the disk 40 has been arranged as heretofore set forth, and shown by Fig. 1, the support 9 is shifted horizontally to bring the edge of the disk in 50 contact with the adjacent emery-wheel 4. At the time that the support 19 is horizontally shifted it is slightly elevated and the edge of the disk is brought to bear upon the highest portion of the emery-wheel, and thereby the 55 weight of the support effects the disk and acts to hold the latter firmly down or in contact with the emery-wheel, and as said disk is gradually ground down the said support gravitates automatically and maintains the 60 edge of the disk in firm and regular engagement with the emery-wheel or grinding element. It will therefore be understood that any irregularities in the disk will be compensated for by the automatic gravitation of the 65 support and a regular grinding of the disk will ensue.

In the operation of grinding the disk it will

be also understood that the latter is gradually revolved in a horizontal plane by the motion of the grinding element with which it is in contact, and the primary adjustment of the disk will be such as to permit this revolution of the disk without loosening the same too much. If the disk should become loose, the grinding operation will regularly proceed in view of the fact that the support 19 will gravitate, and, moreover, at any time that it is desired to shift the support the latter operation can be easily effected by the operator to hold the disk closely to the grinding ele- 70 75 80 85 90 95

ment or draw it away from the latter for inspection or after the grinding operation is completed.

From the foregoing it will be seen that a regular grinding operation can be pursued 85 irrespective of the irregularity of the edge of the grinding-disk, and in view of the simplicity of the entire attachment the expense of manufacture is reduced to a minimum, and its capability of application to any form 90 of grinding-machine renders it of exceptional value and possessed of superior advantages. Though the preferred form of the device has been described and illustrated, changes in the form, proportion, size, and minor details 95 may be resorted to without departing from the principle of the invention.

Having thus described the invention, what is claimed as new is—

1. In a device of the character set forth, the 100 combination of an attachable frame, a vertically-disposed spindle rotatably mounted on said frame, and a disk-support automatically adjustable in a vertical and a horizontal direction on the said spindle and carrying a 105 fixed vertical rod for holding the disk.

2. In a device of the character set forth, the 110 combination with a sharpening-machine having a sharpening element, of a frame having a crank-arm mounted thereon and movable in a horizontal plane and provided with a vertical spindle at its free extremity, and a disk-support shiftable in a horizontal plane and having an automatic vertical movement on the said spindle.

3. In a device of the character set forth, the 115 combination with a sharpening-machine, having a rotatable sharpening element, of a frame comprising upper and lower clamping members removably attached to a portion of said machine, a spindle movably mounted on the said frame, a support vertically adjustable on the said spindle and including an arcuate extension and a handle or grip, and a vertically-disposed rod mounted in the said arcuate extension and the portion of the support thereunder and having an upper extremity to receive the disk to be ground, the said support having a vertical gravitating movement on the spindle.

4. In a device of the character set forth, the 120 combination with a grinding-machine, having a rotatable grinding element, of a frame comprising upper and lower clamping devices,

the upper clamping device having a horizontal arm as a part thereof, a diagonal brace extending from the lower member upwardly through the arm of the upper member and provided with a horizontal table, a crank-arm pivotally mounted on the said table and having a vertical spindle at its free end, and a disk-support having portions thereof engaging the said spindle and freely movable in a vertical direction.

5 A disk-grinding attachment comprising a frame and a disk-support, the said disk-

support being horizontally shiftable and pivotally mounted on a part of the frame and also automatically adjustable in a vertical direction. 15

In testimony that I claim the foregoing as my own I have hereto affixed my signature in the presence of two witnesses.

HOMER H. HUNNICUTT.
